UNITED STATES PATENT OFFICE.

FELIX LESLIE BENNETT, OF HENDRA, NEAR BRISBANE, QUEENSLAND, AUSTRALIA,
ASSIGNOR OF ONE-HALF TO ARTHUR EDWIN CHARLES, OF HENDRA, NEAR BRIS-
BANE, QUEENSLAND, AUSTRALIA.

BODKIN, NEEDLE, OR THE LIKE.

1,356,124.

Specification of Letters Patent.

Patented Oct. 19, 1920.

Application filed April 24, 1919. Serial No. 292,367.

To all whom it may concern:

Be it known that I, FELIX LESLIE BENNETT, a subject of the King of Great Britain and Ireland, &c., residing at Hendra, near 5 Brisbane, in the State of Queensland, Commonwealth of Australia, have invented certain new and useful Improvements in Bodkins, Needles, or the like; and I do hereby declare the following to be a full, clear, and 10 exact description of the invention, such as will enable others skilled in the art to which it appertains to make and use the same.

This invention relates to improved bodkins, or needles, or the like for inserting 15 ribbons, tapes, braids, or other strip or wide material through garments, fabrics, harness, and other articles.

Ordinary bodkins and needles have not 20 spring limbs which will hook, and hold under lateral tension, ribbon or other strip material, and hold wide but flimsy strip material flat and smooth during its insertion. Such hooking and holding are desirable, and 25 by the present invention the bodkin or needle has hooks to pass through the ribbon or other strip or wide material, and it has spring arms to tension the material laterally. For brevity this improved article is called an expansion bodkin or needle.

30 In the drawings Figure 1 shows an expansion bodkin in front view, and Fig. 2 shows it in side view, with dotted lines to show a part of it modified. Fig. 3 shows Fig. 2 modified. Fig. 4 shows the bodkin 35 with its spring limbs somewhat compressed together a piece of strip material being hooked or impaled in place ready for insertion. The tensioning tendency of the limbs is shown by arrows. Dotted lines show a 40 modification of the bodkin head. Fig. 5 shows a needle having spring limbs and hooks. Fig. 6 shows a bodkin holding strip material under tension ready for insertion. Dotted lines show the positions to which 45 parts of the limbs would expand if the strip material were removed. Figs. 7 and 8 show from opposite sides the tail end of a bodkin holding strip material which is wider than the bodkin.

50 In the case of Figs. 7 and 8 it is supposed that the strip material has had two holes

punched in it ready for the bodkin and that the hooks have not sharp points by which to puncture such material.

The invention is not limited to the designs 55 or the proportions of parts shown.

The bodkin head 1 is in any suitable manner made blunt; 1^b shows a head made by coiling a wire partly for strength and to make the limbs springy and 1^c (the dotted 60 head) is a modification of the head 1. A needle pointed head is marked 1^a.

2 and 3 are limbs extending from the head, and diverging either along their whole length or at parts thereof, and having outward spring, the rear of each limb having any suitable hook or loop. Thus 4, 5 are 65 hooks each terminating in a point or tail, which is as shown pointed or sharp as at 6, 7, for puncturing the strip material, but in 70 Fig. 7 the tails 6^a, 7^a are blunt and such tails may be knobbed if desired. The holes punched in the strip material 10, are marked 8, 9. The narrower the strip material the 75 closer together the hooks are to be pressed so that they will be in puncturing positions to carry the strip material.

The spring limbs enable strip materials of various widths to be engaged or hooked as 80 illustrated, whereupon the materials will be tensioned laterally.

The hooks are made of smaller cross-section in some cases (as shown at 4^a, 5^a) than the main body of limbs 2, 3, and these reduced ends are able to easily make in suitable strip material small holes in many cases in which large holes would not be advisable or practicable.

Hooks will vary in details as to sizes and 85 shapes according to users' needs. In some cases they are made detachable from the limbs as exemplified at 4^b, 5^b in Fig. 6, where the rear of one spring limb is in section, the hook shank entering a hole 3^a in the limb and being made to hold to the limb 95 in any suitable manner, as by being screwed in.

The bodkin may be straight, as in firm lines in Fig. 2; or it may be curved as in Fig. 3, or partly straight and partly curved, 100 as shown by a combination of firm and dotted lines in Fig. 2, or be modified fur-

ther. The needle in Fig. 5 can be used to pierce material which would obstruct a blunt headed bodkin.

An easily entered space is however often provided to receive a ribbon or other strip material, as the slot inside a garment hem, and in such cases a blunt bodkin would be used, so as not to catch in the sides of the slot.

10 It will be noted that in practically all forms of the device, the fabric receiving loops open from the points of the hooks, that is, open toward the free end of the bodkin in use. This insures that the fabric
15 be held against possible disconnection from the bodkin, as the fabric is positioned at the bottom of such fabric receiving loop in the drawing operation. The points proper are separated from the fabric receiving loops by
20 an additional loop, that is, there are double loops between each point and the arms of the bodkin. This double loop arrangement insures that in applying the device, the hooks will enter the fabric and be passed
25 around the double loops and by this operation will tend to tension the arms to a degree sufficient to prevent disconnection. Furthermore by this double loop arrangement, the hooks are positioned intermediate of the
30 arms and may be extended in the same general direction as the arms. This prevents the hooks from projecting beyond the material being drawn by the bodkin.

Ordinarily the bodkin limbs are of wire
35 of round or other cross section as with flattened sides which can be after the article is purchased further bent or shaped by a user as may be found desirable. If in drawing the bodkin or needle along, with the
40 strip material behind it it is necessary to pass through a place which is narrower than the full width of the strip material, or of the distance between the limbs 2, 3, that can be done by compressing the limbs
45 toward one another at that place, after which the limbs can be allowed to expand, to again tension the material.

It will be obvious that there may be more than one strip impaled and drawn into place in a garment or so on simultaneously; in fact a considerable thickness of strip or of combined strips may exist for which

other styles of bodkins do not provide. Again, each tail can have one or more separate strips or pieces of material impaled or 55 engaged on it.

As shown by dotted lines in Fig. 8 the advance corners of specially wide stiff material can be if desired cut off so as to allow the material to enter better the space it has 60 to pass through.

The user of a wire bodkin of the kind described may set the limbs closer together or wider apart and may make the hook tails sharp or blunt at will, to regulate the 65 said parts.

Having described this invention, what is claimed by Letters Patent is:—

1. A bodkin having spring arms, hook terminals arranged between and substantially in the plane of the arms to engage a fabric, said arms being tensioned when the hooks are engaged with the fabric to maintain the fabric spread between the hooks. 70

2. A bodkin having spring arms, hook terminals arranged between and substantially in the plane of the arms to engage a fabric, said hooks being each formed with a fabric receiving loop opening in a direction away from the point of the hook. 75

3. A bodkin having spring arms and terminal fabric engaging members arranged between and substantially in the plane of the arms, each of said members having two oppositely-opening loop portions terminating in points. 80

4. A bodkin having spring arms with terminal fabric engaging members arranged between and substantially in the plane of the arms, each of said members having a 90 free end projection substantially in parallelism with the arm, and a double loop portion between such end and the arm.

5. A bodkin having spring arms with terminal fabric engaging loops provided with 95 piercing points between and in the plane of the loops, the feeding of the material from the points onto the loops serving to place the arms under tension to hold the fabric end substantially flat. 100

In witness whereof I have hereunto set my hand.

FELIX LESLIE BENNETT.
